(57) **CLAIM**

The ornamental design for a toy glider, as shown and described.

DESCRIPTION

FIG. 1 is a perspective view, showing the design of a toy glider;

FIG. 2 is a left side view thereof;

FIG. 3 is a right side view thereof;

FIG. 4 is a front end view thereof;

FIG. 5 is a rear end view thereof;

FIG. 6 is a top view thereof; and,

FIG. 7 is a bottom view thereof.

The nose cone shown in broken lines is environment that forms no part of the claimed design.
